UNITED STATES PATENT OFFICE.

SOLOMON MURPHY, OF NORFOLK, NEBRASKA, ASSIGNOR OF ONE-FOURTH
TO JACOB KOENIGSTEIN, OF NORFOLK, NEBRASKA.

RULE ATTACHMENT.

SPECIFICATION forming part of Letters Patent No. 738,225, dated September 8, 1903.

Application filed January 30, 1903. Serial No. 141,188. (No model.)

To all whom it may concern:

Be it known that I, SOLOMON MURPHY, a citizen of the United States, residing at Norfolk; in the county of Madison and State of Nebraska, have invented a new and useful Rule Attachment, of which the following is a specification.

My invention relates to gages, and more particularly to an adjustable head adapted for use upon rules and the like.

It has for its objects the provision of a compact and accurate device of this class which shall be applicable to shafts or members of various widths.

15 In the accompanying drawings, Figure 1 is a top plan view of one form of my improved gage-head. Fig. 2 is an end elevation thereof of looking in the right in Fig. 1. Fig. 3 is a side elevation of the head in place upon a 20 pocket-rule forming a complete gage, and Fig. 4 is a vertical transverse section on the line 4-4 of Fig. 3. Fig. 5 represents a perspective view of the frame detached, showing it as formed from a single piece of metal.

25 Similar characters indicate like parts throughout the several figures of the drawings.

A suitable frame F may be punched out or otherwise formed preferably from a single 30 sheet of steel or the like and be bent to the form illustrated and best shown in Fig. 5, in which 10 is a base on which the rule or other gage-staff may rest, one end being bent beneath the base 10 and spaced therefrom to 35 form the guide 11, the other end being bent at right angles to the base 10 and forms a fixed jaw 12. This end is then folded upon itself and bent downward, then outward to form the offset 13, and then bent upward to form a nut- 40 retainer having a vertical slot 13^a. The base 10 is extended at one side and curved outward and downward below the base, forming a roll-bracket 14, the journal end of which lies in a plane parallel with the base 10. Al- 45 though these parts are preferably made from a single piece, it is obvious that certain of the extensions may be formed separately and riveted upon the base, if desired. Through the guide 11 operates a sliding member J, 50 provided with a jaw portion 15, situated opposite the fixed jaw 12, and a guide portion

16, having a threaded extension or screw 17, extending across the nut-retainer 13 and through the slot therein. Engaging the screw is a nut 18, grooved at 19 to permit it to enter 55 the retainer-slot and having at its outer end a thumb portion 20.

Between the bottom of the guide portion of the frame and the end of the bracket 14 is a stud or rivet 21, upon which is rotatably 60 journaled a contact member or roll 22 of sufficient diameter to project beyond the frame at the end opposite the curved bracket and thus furnish a working face. The curve of the bracket gives it greater power to resist 65 displacement by pressure against the roll. From the same side of the frame, conveniently from the jaw 12, is a projection 23, extending to the same distance from the frame as the edge of the roll and serving as an index. 70

In use the ruler 24 or other suitable bar is placed upon the base 10 between the jaws 12 and 15 and clamped in place by turning the nut 18. To furnish a marking-point, a pencil may be placed at the corner formed by the 75 arc 25 of the rule and the depth at which the line is to be drawn from the edge of the work correctly gaged by setting the point of the index at the proper division of the rule. The roll may then be drawn easily and accurately 80 along even a rough edge and the desired line made. The dimensions of the base may be conveniently such that rules from seven-eighths to one and three-eighths inches in width may be used as a gage-shaft. 85

Having thus described my invention, what I claim is—

1. In a gage-head, the combination with a frame carrying a fixed jaw and a slotted nut-retainer, of a jaw sliding upon the frame and 90 provided with a screw projecting through said slot, a nut grooved to permit it to enter the slot in the retainer and engaging the screw, and a contact-face for coaction with the work.

2. In a gage-head, the combination with a frame provided with a base upon which a gage-shaft may rest, of a bracket extending from the frame and curved outwardly and downwardly and extended inwardly in a plane below and parallel with the base, and a roll 100 rotatably mounted between the frame and bracket beneath the base.

3. In a gage-head, the combination with a frame member of sheet metal furnishing a base, said frame being bent upward at one end of the base to form a fixed jaw and having the other end bent beneath the base to form a guide, of a jaw movable in the guide, and means for moving the jaw.
4. In a gage-head the combination with a frame member of sheet metal furnishing a base, said frame being bent outward and downward with its end spaced from and extended under the base to furnish a bracket, of a roll rotatably mounted between the base and bracket.
5. A gage-head comprising a frame formed from a single sheet of metal having a flat intermediate portion to form a base with one end folded under said base and spaced therefrom to form a guide, and the other end bent

at right angles to the base forming a fixed 20 jaw, the last-mentioned end being folded upon itself and extended below the base, then bent outward and upward to form a nut-retainer, said base having an extension at one side curved outward and downward with its terminal 25 extended under the base in a plane parallel therewith to form a bracket, a roller mounted in said bracket, and a sliding jaw mounted to slide in said guide and carrying an operating-nut adapted for engagement by 30 said nut-retainer.

In testimony that I claim the foregoing as my own I have hereto affixed my signature in the presence of two witnesses.

SOLOMON MURPHY.
